UNITED STATES PATENT OFFICE

164,091

VIBRATING APPARATUS FOR TREATING
HUMAN BODIES

Paul Bertholin, New York, N. Y.

Application May 17, 1950, Serial No. 10,010

Term of patent 14 years

(Cl. D83—1)

To all whom it may concern:

Be it known that I, Paul Bertholin, a citizen of the United States, residing at 118 West 72nd Street, New York, in the county of New York and State of New York, have invented a new, original, and ornamental Design for a Vibrating Apparatus for Treating Human Bodies, of which the following is a specification, reference being had to the accompanying drawing constituting a part hereof.

Fig. 1 is a top plan view of a vibrating apparatus for treating human bodies, embodying my new design.

Fig. 2 is a front elevational view.

Fig. 3 is a side elevational view.

The back and bottom of the vibrating apparatus are plain.

I claim:

The ornamental design for a vibrating apparatus for treating human bodies, substantially as shown and described.

PAUL BERTHOLIN.
